AWNNG

Ralph L. Friend, Cleveland, Ohio, assignor to Ramode, Inc., Cleveland, Ohio, a corporation of Ohio

Application March 12, 1949, Serial No. 1,375

Term of patent 14 years

(Cl. D21—6)

To all whom it may concern:

Be it known that I, Ralph L. Friend, a citizen of the United States, and a resident of Cleveland, in the county of Cuyahoga and State of Ohio, have invented a new, original, and ornamental Design for an Awning, of which the following is a specification, reference being had to the accompanying drawing, forming a part hereof.

In said drawing, Fig. 1 is a front perspective view of an awning showing my new design; and

Fig. 2 is a rear perspective view of such awning. The dominant features of my design reside in those portions thereof which are shown in full lines.

I claim:

The ornamental design for an awning, as shown and described.

RALPH L. FRIEND.
